UNITED STATES PATENT OFFICE.

PAULDING FARNHAM, OF NEW YORK, N. Y., ASSIGNOR TO THE TIFFANY & COMPANY, OF SAME PLACE.

DESIGN FOR A SPOON.

SPECIFICATION forming part of Design No. 26,212, dated October 27, 1896.

Application filed June 15, 1895. Serial No. 552,957. Term of patent 7 years.

To all whom it may concern:

Be it known that I, PAULDING FARNHAM, a citizen of the United States, and a resident of New York city, county and State of New York, have invented a new and original Design for Spoons, Forks, and other Table Utensils, of which the following is a specification.

This invention relates to a design to be imparted to or wrought upon spoons, forks, and other table utensils; and it consists of the novel configuration and ornamentation hereinafter shown and described.

In the drawings, Figure 1 is a front view of a spoon to which part of the design is applied, and Fig. 2 is a rear view of a spoon to which the rest of the design is applied.

The design is composed of two parts, the front face A (shown in Fig. 1) and the back face B. (Shown in Fig. 2.) For the most part the design is confined to the handle; but a portion, more or less, extends over the body of the article, as shown.

The parts A and B of the design are clearly shown in the accompanying drawings, to which reference is made; and I do hereby declare that the drawings accompanying this specification disclose to any one a clear un-

derstanding of the design, and is sufficient to enable such person to use my invention.

The curvature of the bowl of the spoon or 30 of the tines of the fork not being a part of the invention, it is of course immaterial to the invention what curvature is taken by the bowl of the spoon or the tines of the fork to which the design is applied.

What I claim as new, and desire to secure by Letters Patent, is—

1. In a design for spoons, forks and other utensils, the front face A, substantially as shown.

2. In a design for spoons, forks and other utensils, the back face B, substantially as shown.

3. The design for spoons, forks and other utensils, consisting of the front face A and 45 back face B, substantially as shown.

In testimony whereof I have signed my name to this specification in the presence of two subscribing witnesses.

PAULDING FARNHAM.
